UNITED STATES PATENT OFFICE.

ROBERT W. SCOTT, OF BOSTON, MASSACHUSETTS, ASSIGNOR TO SCOTT & WILLIAMS INCORPORATED, OF CAMDEN, NEW JERSEY, A CORPORATION OF NEW JERSEY.

DESIGN FOR A STOCKING.

46,324.

Specification for Design.

Patented Aug. 25, 1914.

Application filed July 28, 1913. Serial No. 781,653. Term of patent 14 years.

To all whom it may concern:

Be it known that I, ROBERT W. SCOTT, a citizen of the United States, residing at Boston, county of Suffolk, and State of Massachusetts, have invented a new, original, and ornamental Design for a Stocking, of which the following is a specification, reference being had to the accompanying drawing, forming part thereof.

The figure is a side view of a stocking embodying my invention folded on a longitudinal plane.

The body and foot of my new and ornamental stocking, shown at A in the drawing, are of an ordinary or usual construction of knit fabric having its face or wale side outward. The ornamental top section B is of an ordinary or usual construction of knit fabric having its face or wale side outward, and having a relatively fine texture. Said ornamental top comprises a finish or welt C of fabric having its loop or back side outward, giving the ornamental effect shown in the drawing.

I claim:

The ornamental design for a stocking as shown and described.

ROBERT W. SCOTT.
